DESIGN FOR A COCKTAIL SHAKER TOP OR SIMILAR ARTICLE

Solomon Shapiro, Cedarhurst, N. Y., assignor to Artercraft Metal and Electrical Products, Inc., a corporation of New York

Application February 14, 1935, Serial No. 55,399

Term of patent 3½ years

To all whom it may concern:

Be it known that I, Solomon Shapiro, a citizen of the United States of America and a resident of Cedarhurst, in the county of Nassau and State of New York, have invented a new, original, and ornamental Design for a Cocktail Shaker Top or Similar Article, of which the following is a specification, reference being had to the accompanying drawing, forming a part thereof. In the drawing:

Fig. 1 is a top plan view of the cocktail shaker top or similar article; and

Fig. 2 is a side elevational view of the same showing my design.

I claim:

The ornamental design for a cocktail shaker top or similar article substantially as shown.

SOLOMON SHAPIRO.
